WEARING APPAREL

Ruth D. Brierley, Bryn Mawr, Pa.

Application June 10, 1952, Serial No. 292,658

1 Claim. (Cl. 2—111)

The object of the invention is to provide improvements in wearing apparel broadly, but more specifically in the sleeve anchorage of undergarments worn by children of tender years and especially young infants, while the sleeves of overgarments are drawn over their arms and such under sleeves, it being understood that the invention may be embodied in garments worn by older children and in fact by adults as well.

As illustrative of the function and utility of the invention, specific reference will be made to the long-sleeved undergarments commonly worn by infants and small children, but without in any sense limiting the invention thereto. In all garments of this category, other than those designed for special wear, the sleeves are of approximately wrist length, and are intended to extend to but not below the wrist, even when covered by an overgarment, such as a dress, nightie, blouse, jacket, coat, snowsuit, and the like, and which are hereinafter referred to as outer garments.

However, as is well known by parents, nurses and all those who have dressed or changed the clothing of small children and babies, there is a long period during which such children are incapable of holding down an undergarment sleeve, while the arm and sleeve are being inserted their full length into the sleeve of an outer garment, and it is this condition that the present invention is designed to and does remedy.

Accordingly, another object is to provide, as a unitary part of the undergarment sleeve, a simple means by which the sleeve end can be readily attached to or slipped over the child's thumb or finger, for a period sufficient to permit the sleeve and the thus covered arm to be inserted their entire length through the sleeve of the outer garment, after which the thumb or finger may be immediately detached from said means.

A further object is to provide a means of this sort, that after having fulfilled its special function during a given dressing period, and withdrawn from said thumb or finger, will in no way annoy the wearer, because it can be detached or entirely withdrawn to an inconspicuous position laterally of the wrist, and preferably extend not beyond the normal wrist length of the sleeve.

Still another object is to provide a thumb or finger-attaching means of this character, comprising an open aperture, or a distendable slit, within and adjacent to the free end of the garment sleeve, or a substantially U-shaped or looped section of flexible fibrous, plastic, metallic, or other suitable substance, such as a cord, chain, or the like, whose ends are normally secured,

either detachably or fixedly, to and within and parallel with the free edge of the sleeve, and preferably of elastic material of such resilient nature, that upon being removed from a temporarily distorted shape and position while extending through the crotch between the thumb and adjacent finger, or otherwise, it will automatically return to its normal shape in retracted position within the limits of said sleeve, thereafter to offer no impediment, obstruction, or annoyance, to the full use of the wearer's hand and fingers.

And still another object is to provide a construction of this general nature, comprising either a small ring adapted to receive one or more fingers, the term finger as herein used also including the thumb as one of the natural group of five fingers of the hand, or a larger ring or wristlet adapted to encircle the palm of the hand or wrist, and in either case being secured to the free end portion of the sleeve by a flexible element, and operative to continue such encirclement, or to be disconnected from said finger or palm and returned to a position within the sleeve, or permitted to depend therefrom where it can function as a teething ring or as a toy, or completely detached therefrom.

With the objects thus briefly stated, the invention comprises further details of construction and operation, which are hereinafter fully set forth in the following description, when read in conjunction with the accompanying drawings, in which Fig. 1 shows a little child having a representative type of undergarment characterized by a pair of wrist length sleeves equipped with flexible resilient elements temporarily extending between the thumb and first finger of each of his hands preparatory to an overgarment being placed upon him with its sleeves drawn over the sleeves of said undergarment; Fig. 2 is an enlarged fragmentary view showing a sleeve end portion, a hand protruding therefrom and a flexible element of the type hereinbefore referred to, this figure being substantially an enlargement of a portion of Fig. 1; Fig. 3 is a similar view to Fig. 2 but with the flexible element in normal retracted position within the free end portion of the undergarment sleeve, and a corresponding portion of the sleeve of an overgarment covering said first sleeve, and portions of both sleeves being broken away; Fig. 4 is a circular representation of the end portion of an undergarment sleeve equipped with the element of the invention as shown in Figs. 1, 2 and 3; Fig. 5 is the end portion of a sleeve provided with an aperture comprising a modification of the broad idea; Figs. 6, 7 and 8

are similar views showing further modifications of the invention.

Referring to Figs. 1, 2, 3 and 4, any representative type of undergarment is shown as comprising a body portion 1 and two wrist length sleeves 2, it being understood that this garment may be a shirt, dress, nightie, blouse, sweater or in fact any kind of garment having wrist length sleeves and likely to be covered, at least occasionally, by an outer garment of any desired type such as a coat, snowsuit, or the like. Then again, the outer garment may be a dress that covers a shirt beneath it, the essential factor being that the garment that is intended to be worn beneath another garment is provided with the anchorage elements hereinafter described.

In this instance the invention is shown as comprising a short length of preferably elastic tape 3, whose opposite ends 4 are secured in any suitable manner, as by stitching, snap-fasteners, hooks-and-eyes, gripper fasteners, or the like, slightly within the free edge 5, so that it can be detached, or when inoperative or retracted position said tape occupies a position approximately parallel with the adjacent edge of the sleeve, from which its central portion is first deflected and then, if of elastic material, stretched slightly so as to permit the passage of the thumb or a finger through the extended loop (Figs. 1 and 2), while the sleeve 6 of an outer garment (not shown in its entirety) is pulled upwardly over the first-mentioned sleeve. During this operation, it is obvious that the looped member 3 holds the under-sleeve down at its intended wrist length position, until the outer sleeve has reached its final position (Fig. 3).

Thereupon, the thumb or finger, as the case may be, is withdrawn from said loop, and the member 3 may be detached or permitted to regain its normal length and return to its normally flat-looped position within the limits of the free edge portion 5 of said inner sleeve (Fig. 3). In this position said member offers no further restraint, tension, or discomfort of any kind to the wearer. Thus, the inevitably aggravating difficulty heretofore of maintaining the sleeve of the undergarment in fully extended or normal position, while the sleeve of an outer garment is pulled upwardly over it, is eliminated since the under-sleeve is held firmly against longitudinal movement or from shifting in any direction, while the over sleeve is drawn into its intended position, whether the over sleeve 15 is of the same or lesser length than said under sleeve.

Referring to Fig. 5, there is here shown a fragmentary end portion of an undergarment sleeve 7, having a free end edge portion 8, adjacent to which the material of said sleeve is provided with any suitably shaped aperture 9, as distinguished from a buttonholelike slit 10 (Fig. 6) with which the end portion of a sleeve 11 is provided adjacent to its free edge 12. In each of these two modifications of the specific means for carrying out the invention, the edge portion of the sleeve is distended slightly beyond the wrist, so that the

respective aperture 9 or the slit 10 is permitted to receive preferably the thumb of the wearer's hand—or one or more of the fingers if necessary—while the sleeved arm is forced through the corresponding sleeve of an over-garment, after which the apertured or slitted end portion of the undergarment sleeve is detached from the thumb or one or more fingers and returned to its normal shape and position.

Referring to Fig. 7, the slight modification here shown is characterized by the fact, that one or more of the final edge courses 13 of thread or warp at the free end of the sleeve 14 are dropped from engagement with the threads of the body of the sleeve, and connected thereto only at their opposite ends, so as to thereby provide a normally flattened gap 13' that is bounded upon one side by an outer "flattening" course that is adapted to be distended, to provide a loop capable of receiving a thumb or finger, as hereinbefore described.

In Fig. 8 is shown a modification in which the body of the sleeve 15 is left undisturbed, except that to it is secured in any suitable manner, either permanently or detachably, a flexible element 16, to the outer end of which is attached a ring 17, that may be either relatively small to encircle a finger or thumb of the wearer, or instead may be relatively large (as illustrated) encircling more than one finger, the palm of the hand, or the wrist of the wearer, and which when disengaged therefrom may serve as a teething ring, pacifier, or toy.

Having thus described my invention, what I claim and desire to protect by Letters Patent of the United States is:

A garment, having a wrist length sleeve having a circumferentially continuous free edge adapted to normally surround the wearer's wrist, in combination with a strap secured at its ends to the inner side of the sleeve and normally in retracted position extending substantially parallel with the end of the sleeve and within its free edge, the said strap being distortable in shape and deflectable, so as to project freely from said sleeve substantially perpendicular to the plane of said free edge, while encircling a finger of a hand whose arm extends through said sleeve, said marginal portion upon being released from such finger automatically returning to its inoperative retracted position wholly within and parallel with the edge of said sleeve.
